UNITED STATES PATENT OFFICE.

HERMAN SAART, OF ATTLEBORO, MASSACHUSETTS, ASSIGNOR TO THE W. H. SAART COMPANY, A CORPORATION OF MASSACHUSETTS.

CIGARETTE-SUPPORTER.

1,140,072.

Specification of Letters Patent. Patented May 18, 1915.

Application filed March 26, 1914. Serial No. 827,258.

To all whom it may concern:

Be it known that I, HERMAN SAART, a citizen of the United States, residing at Attleboro, in the county of Bristol and State 5 of Massachusetts, have invented certain new and useful Improvements in Cigarette-Supporters, of which the following is a specification.

My invention relates to a device intended 10 for supporting cigarettes.

The essential objects of my invention are to provide a means of protecting the fingers of the smoker from the well known stain incident to smoking cigarettes; to render 15 the device adaptable to ladies' as well as men's use; to make it possible to lay the device aside without danger of contact of the lighted cigarette with the article upon which the device rests; and to attain these ends in 20 a structure inexpensive to construct, easy to operate, and ornamental in appearance.

To the above ends essentially my invention consists in such parts and in such combinations of parts as fall within the scope 25 of the appended claims.

In the accompanying drawings which form a part of this specification, Figures 1 and 2 are front and side elevations respectively of my supporter in upright position, 30 showing the same engaging a cigarette, Fig. 3, a plan view of the same without a cigarette, and Fig. 4, a side elevation of the supporter resting upon a surface.

Like reference characters indicate like 35 parts throughout the views.

A ring A is provided to the two flat resilient arms B, preferably formed with a single strip of metal folded upon itself at its central portion to form a loop b which 40 tightly embraces the ring A, to which the loop is preferably soldered. Above the loop b the arms B bend inwardly as at b', and thence outwardly as at b'', and thence preferably slightly inwardly as at b''. The de- 45 scribed bends assist in normally holding the adjacent faces of the arms B in normally tight contact with each other along their outer end portions. Integral with the arms B at the extremities of the latter are arcuate 50 fingers C, adapted to embrace a cigarette. Upon one of the arms B near its finger C are laterally extending inclined lugs D, which form bearings or supports for the device when not in manual use. Integral

with one of the arms B at an intermediate 55 portion is a curved projection E, which may be engaged by the thumb or finger nails to pull one arm B away from its companion arm when it is desired to release or insert a cigarette G such as illustrated in the draw- 60 ings. In the present instance the prong or projection E is formed by cutting out a piece of stock from the body of the arm B leaving a resultant opening e, and that portion of the material which is bent up into the 65 prong E.

It will be observed that the entire device comprises but two pieces of metal, and that the entire mechanism outside the ring is stamped in a single piece. It will be under- 70 stood, however, that the two piece construction described is not intended to be exclusive.

The use of this device as suggested by the drawings may be by placing the finger through the ring A, and by pressing the 75 thumb upon the exterior of the ring, thus holding my device in an upright position as shown in Fig. 2. When it is desired to temporarily lay aside the device while the cigarette is still alive the device rests as shown 80 in Fig. 4 with the bearing lugs D and ring A in contact with the supporting article, so that the cigarette is held out of contact with such article.

What I claim is,—

1. A cigarette supporter comprising a ring, two resilient arms fixed to said ring and provided with clamping fingers upon their free ends, lateral bends intermediate said fingers and ring, and lateral means rigid 90 with one of said arms between said bends and fingers to both elevate and prevent tilting of the supporter.

2. The cigarette supporter described comprising in a single element a pair of substan- 95 tially parallel arms united at one end by a loop and the free ends formed into curved clamping fingers, said arms having lateral projections adjacent the loop, lateral lugs on one arm adjacent the fingers and a pro- 100 jection upon the other arm opposite said lugs.

In testimony whereof I have affixed my signature in presence of two witnesses.

HERMAN SAART.
